US00D877549S

(12) United States Design Patent (10) Patent No.: US D877,549 S
(45) Date of Patent: * Mar. 10, 2020

(54) TABLE

(71) Applicant: NATUZZI S.p.A., Santeramo in Colle (Bari) (IT)

(72) Inventor: Mauro Lipparini, Florence (IT)

(73) Assignee: Natuzzi S.p.A., Santeramo in Colle (Bari) (IT)

() Term: 15 Years

(21) Appl. No.: 29/633,708

(22) Filed: Jan. 15, 2018

(30) Foreign Application Priority Data

Jul. 13, 2017 (EM) 004101210-0046

(51) LOC (12) Cl. 06-03

(52) U.S. Cl.

USPC D6/692

(58) Field of Classification Search

USPC D6/668, 672, 677, 685, 687, 689, 692, D6/692.1-692.6, 698, 707.2, 708, 708.15, D6/708.17, 708.2, 708.23

CPC A47B 7/00; A47B 11/00; A47B 13/12; A47B 3/08; A47B 3/0803; A47B 49/004; A47B 13/023; A47B 2013/024; A47B 2013/025; A47B 2013/026; A47B 2013/027; A47B 13/086
